WILLIAM J. MILLAR, OF BOROUGH OF MCKEESPORT, PENNSYLVANIA.

Letters Patent No. 60,771, dated January 1, 1867.

IMPROVED APPARATUS FOR STEERING VESSELS BY STEAM.

The Schedule referred to in these Letters Patent and making part of the same.

TO ALL WHOM IT MAY CONCERN:

Be it known that I, WILLIAM J. MILLAR, of the Borough of McKeesport, in the county of Alleghany, and State of Pennsylvania, have invented a new and useful Improvement in Steering Vessels by Steam; and I do hereby declare the following to be a full, clear, and exact description thereof, reference being had to the accompanying drawing, forming part of this specification, in which—

Figure 1 is a side elevation of my improved steering apparatus.

Figure 2 is a front view thereof.

Figure 3 is a plan of the tiller-ropes, showing their connection with the self-acting governing lever.

In the several figures like letters of reference denote similar parts.

My improvement consists in the use of an apparatus actuated by steam power to operate upon the tiller of a vessel for the purpose of steering. It is oftentimes a matter of great difficulty to apply sufficient power to the steering-wheel of a vessel to guide it in the desired course or to hold it in position; and even where this is not the case it would be a great saving of labor to have the steering-wheel operated by mechanical power instead of by man power.

To enable others skilled in the art to construct and use my steam-steering apparatus, I will proceed to describe its construction and operation.

In the drawing, (fig. 1,) *a* is the rudder of the vessel, and *b* the tiller. *c c'* are the tiller-ropes, attached to the tiller in the ordinary manner, and which extend forward, over pulleys and rollers, to the steering-wheel, *d*, which is placed in any usual and convenient position. The arrangement of the ordinary appliances for steering, which are applicable to my improvement, as I shall describe them in this specification, are those in use in steam-boats on the western waters; but my apparatus may be readily adapted, by obvious modification of arrangement, to any ordinary steering apparatus or relative position of tiller and steering-wheel. The starboard and larboard tiller-ropes, *c* and *c'*, are wound around the drum, *e*, of the steering-wheel *d*, in opposite directions, so that by turning the wheel *d* in either direction the tiller is operated accordingly. In steam vessels in which a small auxiliary steam engine is employed for the purpose of hoisting and lowering freight from or into the hold of the vessel, it is most convenient to employ that engine for operating the steering apparatus. Such an engine, commonly called "the nigger," is used on the steamboats plying on the Ohio and Mississippi rivers and their tributaries. In the drawing, *f* is the cylinder of the nigger engine, and *g* the steam-chest for the admission of steam. *h* is a lever which operates a valve by which the engine is started or its operation reversed. *k* is the piston-rod of the cylinder *f*, and *l* is a crank to which the piston-rod is attached, and by which the shaft, *i*, is caused to revolve. *n n'* are two mitred cog-wheels, one fixed to the shaft *i*, and the other to the vertical shaft, *m*, on top of which is another mitred wheel, *o*, which gears into a mitred wheel, *o'*, on the shaft of the steering-wheel *d*. By means of this connection of shafting and gear-wheels, the operation of the nigger engine causes the steering-wheel to revolve in either direction, according as the cut-off lever *h* is inclined backwards or forwards; but when the cut-off lever is in an upright position the steam is shut off and the steering-wheel is at rest. The cut-off lever *h* is operated by means of a hand lever, *p*, placed near the steering-wheel, or wherever the pilot-house is situate, as it is not necessary that the steering-wheel should be placed in or near the pilot-house unless preferred, if only the lever for operating the engine which gives motion to the steering-wheel is suitably placed. One end of the pilot lever *p* is attached by a rod, *q*, to a bent lever, *r*, to which the cut-off lever is attached by a rod, *s*. By moving the pilot lever *p* up or down, the steering-wheel is immediately set in motion, and the tiller moved to starboard or larboard as the lever is moved in one direction or the other. When the lever is in a horizontal position the steering-wheel is at rest. The arrangement described for operating the steering-wheel by steam power, regulated by the mere motion of a lever, would be subject to the serious objection that the engine might be allowed to run, by inadvertence or carelessness, so long in one direction as to break the tiller-ropes, for when the rudder is hard up on either side, and can go no further, the rope being still forcibly wound around the drum of the steering-wheel, something would give way. To remedy this difficulty I have contrived a plan for causing the tiller-ropes, when the tiller is moved to its utmost extent in either direction, to operate the cut-off lever so as to stop the engine. This is effected as follows: A horizontal lever, *t*, (fig. 3,) is placed between one of the tiller-ropes *c* and the rod *s*, which is attached to and operates the cut-off

lever h . The check lever t has its turning point at u , between the tiller-rope c and rod s , and is pivoted to the rod s in such a manner as that the moving of the lever t will operate the cut-off lever in the same manner as the pilot lever p . The other extremity of the check lever has a ring through which the tiller-rope passes freely without acting upon the lever; but on the tiller-rope are fastened two knobs or buttons, v x , which are too large to pass through the ring at the extremity of the lever, one on each of the check levers, at such a distance therefrom that the knobs do not, either of them, come in contact with the lever until the tiller-rope is drawn so far as to move the tiller to its furthest limit. At this point, or just before the tiller reaches its furthest limit, one of the knobs comes in contact with the lever, and turning it on its pivot, operates the rod s until the cut-off lever h assumes a vertical position, when the engine stops, leaving the tiller in the position which it had reached. Thus the possibility of the engine running so long as to strain or break the tiller ropes is effectually prevented.

Having thus described my improvement, what I claim as my invention, and desire to secure by Letters Patent, is—

1. The combination of the levers p and r , and the cut-off lever h , of the nigger engine, with the steering-wheel d and the gear-wheels n , n' , o , and o' , connecting it with the engine, constructed and arranged substantially as and for the purposes hereinbefore described.

2. Also the check lever t , operated by means of stops or buttons on the tiller-rope, in combination with the cut-off lever of the steam engine, constructed and operating substantially as hereinbefore described for the purpose of stopping the steering engine when the tiller is turned to its utmost limit in either direction.

In testimony whereof I, the said WILLIAM J. MILLER, have hereunto set my hand in presence of—

WILLIAM J. MILLAR.
